UNITED STATES PATENT OFFICE

HARRY SMICK, OF YAKIMA, WASHINGTON

AIR CLEANER AND FILTER

Application filed January 26, 1931. Serial No. 511,318.

My invention relates to air cleaners and filters and more particularly to cleaners and filters that are adapted to be installed on the air intake sleeves of carburetors for internal combustion engines and the like. Certain objects of the invention are to provide an air cleaner and filter embodying means for removing the dust from the entering air which causes scratching and scoring of the cylinders and comprising novel fabric filter and retainer means therefor, novel entry means for directing the air against oil whereby the dust is caused to adhere thereto, and novel baffle means for preventing the oil from being sucked into the engine by the force of the air on the intake stroke.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

25 Figure 1 is a general view in side elevation showing the device mounted in connection with the engine of a motor vehicle;

Fig. 2 is a view in central vertical section of the device;

30 Fig. 3 is a bottom plan view of the upper casing member of the device;

Fig. 4 is a top plan view of the lower casing member;

35 Fig. 5 is a view in vertical section of the lower casing member taken on a broken line 5, 5 of Fig. 4; and

Fig. 6 is an inverted perspective view of a fragmentary portion of the upper casing member showing the rim locking means for 40 the lower wire screen.

Referring to the drawings throughout which like reference numerals indicate like parts, the numeral 5 designates the upper cylindrical casing member and 6 designates the lower casing member whose upper edge is adapted to telescopically receive the lower edge portion of said upper member and both of said members are provided with a bead 7 which beads serve as stops for the respective edges of the members as shown in Fig. 2 of

the drawings. Said upper casing member is provided at its top with an outlet nozzle 8 that is adapted to be connected by means of a pipe 9 with a carburetor 10 of a motor vehicle engine 11 as shown in Fig. 1.

55 The upper casing member 5 is internally provided with a horizontal screen or wire mesh partition 12 fixed within its top portion of any desirable means. A mass of steel wool or other like fabric 13 is filled into said upper casing member and pressed upwardly against said screen. The steel wool or other fabric is preferably in one piece so that, with the aid of said screen, small particles or strands of the fabric are prevented from being sucked into the carburetor by the intake stroke of the engine as will be understood.

60 The steel wool or other filter fabric 13 is held upwardly within the upper casing member 5 by means of a lower screen or wire mesh 14. The peripheral portion of said lower screen is provided with a metal rim 15 that is provided with outer edge slots 16. Lugs 17 are fixed to the inner wall of said casing member in spaced relation corresponding with the spacing of the slots. Said lower screen is pushed upwardly against the filter fabric until the slots in its rim pass by said lugs and then, by means of small handles 18 fixed to the underside of the screen rim as shown in detail in Fig. 6, the screen is slightly turned to lock it in place against the filter fabric.

65 A quantity of comparatively heavy oil, as shown at 19 in Fig. 2, is placed in the bottom of the lower casing member 6. Said lower casing member is provided on its exterior upper portion with a pair of diametrically opposite air intake ports 20 whose bottoms slant downwardly to direct the incoming air against the oil as indicated by direction arrows. Said intake ports are screened by fine wire meshes 21 which prevent heavy particles of dirt from entering the device. The in-rushing air strikes the oil which removes the coarse or heavy dust by adherence thereto as will be understood.

70 A horizontal baffle plate 22 is installed within the upper portion of the lower casing member 6. Said baffle is substantially the

same width as the diametrically opposite air entry ports 20 and is disposed in alignment therewith for the purpose of preventing the force of the air from sucking the oil 19 upwardly. The lateral edges of said baffle plate are bent downwardly, as at 23, which additionally prevents the oil from being sucked upward and directs it back into the bottom of said lower casing member. Said baffle is centrally provided with an aperture 24 for upward passage of the air and which aperture also serves to centralize the air as it rebounds upwardly from the surface of the oil.

An upstanding elliptical shaped baffle 25 is provided in the bottom of the lower casing member 6. The major axis of said baffle extends entirely across said lower casing and at right angles to the horizontal baffle plate 22. Said baffle prevents the air from causing excessive agitation of the oil and also aids in preventing it from being sucked upwardly by the force of the air. The bottom of said baffle is cut away, as at 26, so that the oil may circulate and absorb the dirt more evenly and completely that is deposited therein.

The means for fastening the upper and lower casing members 5 and 6, respectively, together comprises a pair of long bolts 27 that are pivotally secured at diametrically opposite points, as at 28, to the said upper casing member whereby they may be swung outwardly. The lower threaded ends of said bolts are arranged to engage into slots 29 provided in the ends of a yoke plate 30 which fits across under the bottom of said lower casing and is held securely by wing nuts 31 as will be understood. This arrangement provides means whereby the lower casing may be readily removed and cleaned and the oil renewed.

In the operation of the device the heavy dust is removed by adherence to the oil 19 as hereinbefore set forth, and the fine dust is removed by the filter fabric 13 during the passage of the air therethrough as indicated by direction arrows in Fig. 2. It will now be apparent that I have provided means for delivering clean air to the engine whereby a purer mixture of fuel is effected and scoring and scratching of the engine cylinder walls by dust and other foreign matter is prevented.

Having thus described my invention, it being understood that minor changes in the construction and arrangement of the device may be resorted to without departing from the scope and spirit of the invention, what I claim and desire to secure by Letters Patent of the United States is:—

1. An air cleaner and filter having in combination an upper casing member, an outlet nozzle whereby said upper casing is adapted to be connected to the air intake of an internal combustion engine, a wire screen partition for the upper interior portion of the upper casing member, a mass of filter fabric packed against said screen, a lower wire

screen, lugs secured to the lower casing wall, a rim for the lower screen having peripheral slots arranged to receive said lugs and retain said screen in fastened position against the bottom of the filter fabric, a lower casing member adapted to telescopically receive the edge portion of the upper casing member, means for detachably fastening said lower and upper casings together, diametrically opposite air entry ports for the upper portion of the lower casing member having screened openings, oil disposed in the bottom of the lower casing member, the bottoms of said entry ports slanting downwardly whereby the entering air is directed against the oil, a horizontal baffle plate substantially equal in width to the entry ports and disposed in alignment therewith, said baffle having a central aperture, and an upstanding baffle disposed across the bottom of the lower casing at right angles to the horizontal baffle plate.

2. An air cleaner and filter having in combination an upper casing member, an outlet nozzle whereby said upper casing is adapted to be connected to the air intake of an internal combustion engine, upper and lower screen partitions for the upper casing member, filter fabric packed between said screens, means for securing the lower screen against said fabric, a lower casing member, means for detachably fastening said lower and upper members together, diametrically opposite air entry ports slanting downwardly from the upper portion of the lower casing, oil disposed in the bottom of the lower casing member, a horizontal baffle plate disposed in alignment with the air entry ports, and said baffle having a central aperture.

In testimony whereof I affix my signature. 105
HARRY SMICK.
